(57) **CLAIM**

The ornamental design for a jump rope package, as shown and described.

DESCRIPTION

FIG. 1 is a plan view of a jump rope package; and, FIG. 2 is a similar plan view thereof, with hands of a person illustrated thereon and with the jump rope, shown in broken lines for environmental purposes only, extending through openings so as to provide the appearance of the illustrated hands holding a physical jump rope supported by the package.

The parts illustrated in broken lines are not part of the claimed design. Thus, other than the hands and the shape of the supporting sheet or board in the area of the hands, the illustration appearing on the surface of the supporting sheet or board and overall outline of the supporting sheet or board are not part of the present design.
